SAIL HOOK

Kenneth B. Cochran, Costa Mesa, Calif., assignor to
Olympic Products Company, Los Angeles, Calif., a corporation of California

Filed Oct. 15, 1964, Ser. No. 82,187

Term of patent 14 years

(Cl. D54—11)

FIG.1

I claim:

The ornamental design for a sail hook, substantially as shown.
